Primary Examiner — Ricky Pham*(74) Attorney, Agent, or Firm* — Banner & Witcoff, Ltd.**CLAIM**

The ornamental design for a mixer, as shown and described.

DESCRIPTION

FIG. 1 is a perspective view of a mixer showing my new design;

FIG. 2 is a front view thereof;

FIG. 3 is a top view thereof;

FIG. 4 is a bottom view thereof;

FIG. 5 is a left side view thereof;

FIG. 6 is a right side view thereof;

FIG. 7 is a rear view thereof;

FIG. 8 is a front perspective view of the mixer of FIGS. 1-7 shown by a different CAD representation style;

FIG. 9 is a front view thereof;

FIG. 10 is a top view thereof;

FIG. 11 is a left side view thereof;

FIG. 12 is a right side view thereof;

FIG. 13 is a rear view thereof; and,

FIGS. 14 and 15 are color photographs of a commercial embodiment corresponding to the mixer shown in FIGS. 1-13.
